EDUCATIONAL DIAL FOR A CLOCK

Norman C. Shellman, Winnetka, Ill.

Application November 2, 1953, Serial No. 27,405

Term of patent 14 years

(Cl. D25—1)

To all whom it may concern:

Be it known that I, Norman C. Shellman, a citizen of the United States, and a resident of Winnetka, in the county of Cook and State of Illinois, have invented a new, original, and ornamental Design for an Educational Dial for a Clock, of which the following is a specification, reference being had to the accompanying drawing, forming a part thereof, and in which:

Fig. 1 is a top plan view of an educational dial for a clock showing my new design; and

Fig. 2 is an edge view of the same to reduced scale.

I claim:

The ornamental design for an educational dial for a clock, as shown.
